UNITED STATES PATENT OFFICE.

WILLIAM LEE BURNAM, OF KANSAS CITY, MISSOURI.

VARIABLE RESISTANCE.

Application filed January 27, 1926. Serial No. 84,206.

This invention relates to a liquid rheostat which is adapted for use as static eliminator.

An object of this invention is to provide a simple and efficient variable resistance device which is adjustable and adapted to be connected preferably between the aerial and the antenna post of a radio set, whereby the resistance of the circuit can be varied and static and other disturbing frequencies eliminated.

A further object is to provide such a device which is simple to operate and durable and economical in construction.

The invention is illustrated in the drawings, of which—

Figure 1 is a side elevation of the device mounted on the panel board;

Figure 2 is a longitudinal section through the device taken on the line 2—2 of Figure 1;

Figure 3 is a longitudinal section taken at right angles to the section line of Figure 2;

Figure 4 is a horizontal section taken on the line 4—4 of Figure 3.

The form of the invention shown in the drawings is a preferred form, although it is understood that modifications in the construction and arrangement of the parts and the character of the materials used may be adopted without departing from the spirit of the invention as set forth in the appended claims.

In its general aspect the invention comprises a tubular container in which a body of liquid is disposed. Disposed within the container is an adjustable electrode which may be wholly or partly submerged in the liquid. One end of the container is connected to the antenna circuit, for instance, and the other end is connected to the radio set. By adjusting the distance between the bottom of the adjustable electrode and the bottom of the container the resistance in circuit can be varied and it is found that this arrangement will permit radio signals to pass and at the same time will shut out the static and other extraneous noises. It also seems to decidedly improve the quality of the tone coming from the set. The adjustable electrode is manipulated by a knob which extends through the side of a container and may be mounted on the side of a panel board.

In the preferred construction shown in the drawings, the invention comprises a container 10, preferably in tubular form, made of any material which will hold water and is

not a conductor of electricity. The upper and lower ends of the container are closed by threaded caps 11 and 12 which are screwed on the ends of the tube, packing rings 13 and 14 making the joint tight. The caps are provided with threaded stems 15 and 16 on which thumb nuts 17 and 18 are mounted for the purpose of permitting connection to conducting wires. Within the container or tube is a body of liquid 19 preferably water. Dependent into the liquid is an electrode 20 mounted on a rack bar 21 which is slidable in a curved guide plate 22. This guide plate is fastened against the face of an insulating block 23 which is screwed to the side of the tube 10. An insulating sleeve 24 is threaded into an aperture in the block 23 and an aperture in the side of the tube and in the panel board 25. Suitable washers 26 and 27 are disposed on each side of the panel board and threaded on this sleeve 24. Within the sleeve is a shaft 28 on the outer end of which is mounted a knob 29 with a pointer 30 traveling over a dial 31. The other end of the shaft 28 is provided with a pinion 32 engaging with the rack bar 21 to move it upwardly and downwardly. As shown in Figure 2 one side of the guide plate 22 is split to provide a spring finger 33 which will frictionally bear against the rack bar to maintain it in any position in which it is left. The guide plate 22 supports a spring arm 34 which extends upwardly therefrom and bears as at 35 against the bottom of the cap 11, thus making the circuit contact with the binding post stem 15, the caps 11 and 12 being of metal. It will be observed that as the knob 29 is operated to raise and lower the rack bar the distance between the bottom of the electrode 20 and the cap 12 through the liquid 19 can be varied, thus varying the resistance introduced into the circuit by reason of this liquid path through which the signal currents have to pass. It is the provision of this variable liquid path in the circuit, preferably the antenna circuit, which seems to cause the improvement in the operation of the set and in the elimination of static.

What I claim is:

1. In a variable resistance, a liquid receptacle of insulating material provided with metal caps having means for securing circuit wires thereto, a guide member in the receptacle, a rack mounted in the member, an electrode carried by the rack, a pinion meshing

with the rack, means for operating the pinion, and a member carried by the guide member and permanently engaging the upper cap of the receptacle.

- 5 2. In a variable resistance, a liquid receptacle of insulating material provided with metal caps having means for securing circuit wires thereto, a guide member in the receptacle, a rack slidably mounted in the member, a spring carried by said member and engaging the rack to hold it in position, an electrode carried by the rack, a pinion meshing with the rack, means for operating the pinion, and a member carried by the guide member and permanently engaging the upper cap of the receptacle.
- 10 3. In a variable resistance, a tubular liquid

receptacle of insulating material provided with removable metal caps having threaded stems on which thumb nuts are mounted, an insulating block secured to the casing, a guide secured to said block, a rack slidably mounted in the guide, an electrode secured to the lower end of the rack, a spring carried by the guide and engaging the rack, an insulating sleeve in openings in the insulating block and the receptacle, a shaft mounted in the sleeve and provided with a knob at its outer end, a pinion on the inner end of the shaft and meshing with the rack, and a spring arm secured to the guide and permanently engaging the upper cap of the receptacle.

WILLIAM LEE BURNAM.
